UNITED STATES PATENT OFFICE.

JOHN PRESCOTT SANBORN, OF CLEVELAND, OHIO, ASSIGNOR TO THE NATURA COMPANY, A CORPORATION OF OHIO.

RECTAL APPARATUS.

942,590.

Specification of Letters Patent. Patented Dec. 7, 1909.

Application filed January 2, 1899. Serial No. 470,485.

To all whom it may concern:

Be it known that I, JOHN PRESCOTT SANBORN, a citizen of the United States of America, residing at Cleveland, in the county of Cuyahoga and State of Ohio, have invented certain new and useful Improvements in Rectal Apparatus; and I hereby declare the following to be a full, clear, and exact description of the invention, such as will enable others skilled in the art to which it pertains to make and use the same.

The present invention relates to improvements in apparatus for curing rectal disorders such as piles and constipation and relates particularly to an apparatus adapted to be worn by the person afflicted with such a disorder, and having an attachment which will engage the affected parts in a manner such as to exert a continuous healing action.

One of the objects of the invention is the provision of an apparatus of the above character, which is more efficient and effective in results attained than the devices heretofore employed for the same purpose.

A further object is the provision of an apparatus which may be applied to the body and worn continuously without causing discomfort and which may be readily adjusted so as to conform to a body of any size or proportions.

The invention may be briefly summarized as consisting in certain novel combinations and arrangements of parts which will be described in the specification and set forth in the appended claims.

In the accompanying drawings Figure 1 is a front view of the apparatus applied to the body. Fig. 2 is a rear view of the apparatus detached from the body. Fig. 3 is a side view of the same. Fig. 4 is an enlarged sectional view of an attachment or device which is carried by a strap designed to extend under the crotch of the user. Fig. 5 is a plan view of a modified form of the attachment. Fig. 6 is a side elevation of the same.

Referring now to the figures of the drawings, 10 represents a strap or belt which is adapted to be placed about the waist of the body as shown in Fig. 1, and this belt carries a strap 11 which is adapted to extend under the crotch of the body and is secured to the belt at the front and rear. At the front the strap is divided, both ends being secured to the belt, and at the rear the end

of the strap is adjustably secured to the belt, in the present case, by means of a buckle 12. The divided portion of the strap is covered by rubber 13 or other smooth substance to prevent abrasion or chafing of the skin.

Carried by the strap 11 is a rectal device or attachment 14 the preferred construction of which is shown in detail in Fig. 4. This device as here shown, consists of a clip or plate 15 the sides 16 of which are doubled over so as to form a slot or groove which receives the strap and having on one side a rounded projection 17 which is adapted to engage and bear against the anus, and consisting also of a tubular or hollow cylindrical member 18 which extends outward through an opening in the center of the rounded projection and is adapted to extend into the rectum. This member 18 has a rounded closed outer or free end and is held in position and prevented from shifting outward by a shoulder 19 and is held against inward movement by a base plate 20 which fits in an opening in the clip and which is provided with a boss or projection 21 which extends into the mouth of the tubular member. It is to be understood that the member 18 will be inserted in place before the strap is passed through the clip, and after the strap is in place it will hold the base plate and tubular member in position. It may be stated that this member, which is preferably formed of zinc, serves as a dilator to assist the cure of constipation and as a remedy for the cure of piles and particularly of that type consisting of internal hemorrhoids. The member is therefore provided with a number of perforations 22 and contains a suitable remedy 23 preferably in the form of a bar or cylinder which will soften by the heat of the body so as to flow or pass through the perforations onto the hemorrhoids. In order that this remedy may always be in position to flow out through the perforations, I have provided means for feeding the same forward or toward the outer end of the tube and this means consists of a plunger, plug or piston 24 in the tubular member and a spring 25 which bears against the boss or projection 21 of the plate 20 at the inner end of the member and against the plunger in a manner such as to tend to force the latter outward continuously.

It will be seen that the device 14 may be readily adjusted along the strap so as to occupy a position opposite the anus. When the device is in position the tubular member 18 will extend into the rectum and will act in the manner above described and at the same time the rounded projection 17 at the base of the tubular member 18 will press the protruding hemorrhoids into the rectum and hold them there as long as the apparatus is worn. The tubular member is formed of zinc for the reason that, as is well known, this metal has healing properties.

In Figs. 5 and 6, I have shown a rectal device similar to the one shown in Fig. 4 with the exception that the tubular member is omitted. As shown in these figures the device consists of a metal clip 15^a which is adjustable along the strap as in the first instance and is provided with a rounded projection 17^a which as described above will bear against the anus and hold into the rectum the hemorrhoids which would tend to protrude beyond the anus or sphincter muscle.

I do not desire to be confined to the exact details shown, but aim in my claims to cover all modifications which do not involve a departure from the spirit and scope of my invention.

What I claim as new and desire to secure by Letters Patent is:—

1. In a rectal apparatus adapted to be worn on the body, a strap to extend under the crotch said strap having mounted thereon a rectal device comprising a member having a rounded projection adapted to bear against the anus and a tubular member extending centrally from said rounded projection, and adapted to be inserted into the rectum.

2. In a rectal apparatus adapted to be worn on the body, a strap adapted to extend under the crotch, a rectal device slidably mounted on said strap comprising a tube adapted to extend into the rectum, said tube

having a number of perforations and containing a healing remedy, and means for exerting a continuous pressure on the latter so as to force the same outward toward the outer or free end of the tube.

3. In a rectal apparatus adapted to be worn on the body, a strap extending under the crotch, and having mounted thereon a rectal device comprising a plate having a tube extending therefrom and adapted to be placed in the rectum, said device having at the base of the tube a rounded projecting member adapted to bear against the anus, said tube having near its free end a number of perforations and containing a healing remedy, and means in said tube exerting a continuous pressure on the remedy to force the same along the tube toward the perforations.

4. In a rectal apparatus adapted to be worn on the body, a belt adapted to encircle the waist, an adjustable strap adapted to extend under the crotch and secured to said belt at the front and rear thereof, and a rectal device mounted on said strap and capable of adjustment thereon, said device comprising a plate having a groove through which the strap extends and having a rounded projection adapted to bear against the anus, and a tubular member extending centrally from said rounded projection and adapted to be placed in the rectum, said tubular member having near the outer or free end a number of perforations and containing a healing remedy, a piston or plunger in said member, and a spring bearing against the plunger to force the same and the remedy outward.

In testimony whereof, I sign the foregoing specification, in the presence of two witnesses.

JOHN PRESCOTT SANBORN.
